UNITED STATES PATENT OFFICE.

HENRY GREY, OF DULUTH, MINNESOTA, ASSIGNOR TO THE AMERICAN UNIVERSAL MILL COMPANY, OF NEW YORK, N. Y.

ROLLING-MILL.

SPECIFICATION forming part of Letters Patent No. 635,381, dated October 24, 1899.

Application filed November 29, 1897. Serial No. 660,039. (No model.)

To all whom it may concern:

Be it known that I, HENRY GREY, of Duluth, in the county of St. Louis and State of Minnesota, have invented certain new and useful 5 Improvements in Rolling-Mills; and I do hereby declare the following to be a full, clear, and exact description of the invention, such as will enable others skilled in the art to which it pertains to make and use the same.

10 My invention relates to improvements in mills or apparatus for rolling metallic beams, girders, columns, &c.

This invention pertains more especially to a mill that comprises, first, two horizontal 15 rolls arranged the one above the other in the same vertical plane and in position to operate upon the blank's web and upon the inner sides of the heads or flanges of the blank and having the upper horizontal roll adjustable 20 vertically; secondly, two vertical rolls arranged at opposite ends, respectively, of the horizontal rolls and in position to operate upon the outer sides of the blank's heads or flanges; thirdly, another system of rolls comprising 25 two horizontal rolls arranged the one above the other and in position to operate upon the edges of the blank's flanges in the passage of the blank to or from the first-mentioned roll system; fourthly, means for overturning the 30 work at one end of the work's path; fifthly, side guides arranged between the two roll systems at opposite sides, respectively, of the work's path, and, sixthly, two blank-straightening bars arranged at opposite sides, respectively, 35 of the work's path and operated as required to gradually effect the straightening of the blank during the latter's reduction.

My present invention relates more particularly, first, to the simple, durable, and inexpensive means employed for actuating the slides that support the upright rolls toward and from each other; secondly, to the peculiar mechanism employed in actuating the aforesaid side guides simultaneously toward and from 45 each other; thirdly, to the means employed in the operation of the aforesaid straightening-bars and involving, broadly, straightening-bars simultaneously actuated toward and from each other and actuated more rapidly 50 in their adjustment than the aforesaid slides; fourthly, to the peculiar mechanism employed

in overturning the work upon a feed-table that is arranged below one end of the work's path, and, fifthly, in providing each of the flange-edge-rolling rolls between the flange-edge- 55 rolling portions of the rolls with a collar and in having the diameter of the collar of each flange-edge-rolling roll such that the distance between the periphery of the collar and the periphery of the flange-edge-rolling portions 60 of the roll shall agree with the distance between the edges of the work's flanges and the adjacent surfaces of the web of the work, so that it shall be possible with the one set of rolls to make one size of beam, and as the 65 piece is overturned any given number of times until the edges of the beam have a bearing upon each of the said rolls the beam when completed will of course have a uniform cross-section throughout. 70

My invention consists also in certain other novel and meritorious features of construction and combinations of parts, hereinafter described and pointed out in the claims.

In the accompanying drawings, Figure I is 75 a top plan of my improved mill or apparatus, portions being broken away and in section in this figure to reduce the latter's size and to more clearly show the construction. Fig. II is an elevation of the roll system B employed in rolling the sides of the webs and heads or flanges of the work, partly in section on line II II, Fig. I. Fig. III is a top plan of roll system B, portions being broken away and in section in this figure to more 85 clearly show the construction. Fig. IV is a top plan of the apparatus or machinery employed in simultaneously driving all of the horizontal rolls of the mill. Fig. V is an elevation of the roll system employed in operating 90 upon the edges of the work's heads or flanges and showing also a portion of the machinery instrumental in driving the said rolls. Fig. VI is an elevation showing the web-reducing rolls in end elevation and the 95 operative connection between the blank-straightening bars and the shaft that is instrumental in the rotation of the screws employed in the adjustment of the top web-reducing roll and showing also the operative 100 connection between the said shaft and the screw employed in the adjustment of an up-

right flange - reducing roll. Portions are broken away in Fig. VI to show a half-box for the top web-reducing roll. Fig. VII is an elevation of roll system A employed in 5 rolling the edges of the heads or flanges of a blank and in straightening, smoothing, or removing scales from the web, partly in section on line VII VII, Fig. I. Fig. VIII is an elevation of roll system A at line VIII VIII, 10 Fig. VII, and shows the flange-edge-rolling rolls engaging the flanges and webs of the blank. Fig. IX is an elevation, partly in vertical section, showing in detail the operative connection between an upright side roll 15 Fig. VII, and employed in reducing the flange of a blank and the top web-reducing roll. Fig. X is a horizontal section on line X X, Fig. IX. Fig. XI is a side elevation, mostly in vertical section, of the mill's feed-table that is provided 20 with work-overturning apparatus. Fig. XII is a transverse vertical section of the said table.

My improved apparatus or mill for rolling columns, beams, or girders comprises two 25 systems of rolls—one roll system A for rolling the edges of the heads or flanges of the column, beam, or girder (that is hereinafter termed the "blank" or the "work" or the "product") and another roll system B for 30 rolling opposite sides of the flanges or heads and the web of the work. The two roll systems A and B are located in line and preferably in such proximity to each other that the blank or work can be fed from the one system 35 to the other, and the work in feeding it from the one to the other roll system shall be received by the latter before it has left the former, and the rolling or operating surface of the rolls of both systems of rolls are driven 40 positively and in the direction required to feed in opposite directions alternately, and the work is given as many passes through the mill as are required to complete the rolling or shaping of the work, and the blank or work 45 is of course suitably heated preparatory to its introduction into the said rolling-mill, and the work is fed through the mill with its web arranged horizontally.

The roll system B (see Figs. II and III) 50 comprises a top horizontal roll B', a bottom horizontal roll B², and two vertical side rolls D and D, arranged at opposite ends, respectively, of said horizontal rolls, and all of said rolls are positively rotated in the direction 55 required to feed the work, as will hereinafter appear. Roll B' is arranged horizontally and transversely of the work's path in position to operate upon the upper side of the web of the work and upon the inner sides of 60 the work's flanges or heads above the web. Roll B² is arranged below and transversely of the work's path in position to operate upon the lower side of the work's web and upon the inner sides of the work's heads or flanges 65 below the web. The two upright rolls D and D are arranged at opposite sides, respectively, of the work's path in position to op-

erate upon the outer side of the adjacent flange or head of the work. The work C is shown in position in Fig. II. Rolls B' B² are 70 of course rotated in opposite directions, respectively.

Roll system A (see Figs. VII and VIII) comprises, preferably, two rolls A' and A⁺, arranged at the top and bottom, respectively, of the work's path, in position to operate upon the edges of the flanges or heads of the work—that is, the top roll A' operates upon the upwardly-presented edges, and the bottom roll A⁺ operates upon the downwardly-presented edges.

Two feed-tables C' and C² are arranged at opposite ends, respectively, of the work's path through the mill. Feed-table C' is located adjacent to roll system B and is provided with any suitable number of suitably-driven feed-rollers C³. Feed-table C² is located adjacent to roll system A and comprises any suitable number of suitably-driven feed-rollers C⁴. The work is fed from one of 90 the feed-tables to the other feed-table and is passed in opposite directions alternately.

Any mechanism or apparatus suitable for positively driving rolls B' B² of roll system B and rolls A' and A⁺ of roll system A is 95 provided, and in the case illustrated a trunnion A¹² of the lower roll A⁺ of roll system A (see Fig. V) is operatively connected, by means of a suitable coupling or connection A¹⁴, with a suitably-supported horizontally-arranged shaft a, and a trunnion A³ of the upper roll A' is operatively connected, by means of a suitable coupling or connection A¹⁵, with a horizontal shaft a', arranged 100 above and parallel with shaft a. Two spur-gears a² a³, operatively mounted upon shafts a and a', respectively, and having a corresponding number of teeth, mesh with each other, and gear a² meshes with a driving-pinion a⁴, operatively connected in any approved manner with a suitably-supported and suitably-actuated driving-shaft a⁵. Hence rolls A' and A⁺ are driven in opposite directions, respectively, as required. Another pinion a⁶ (see Fig. IV) is operatively mounted 115 upon driving-shaft a⁵ and meshes with a spur-gear a⁷, operatively mounted upon a horizontal shaft a⁸, suitably supported at one side of and a suitable distance from shaft a⁵ and operatively connected, by means of suitable 120 couplings or connections a⁹, with a spur-gear a¹⁰, arranged in line with shaft a⁸ and between said shaft a⁸ and the trunnion b' (see Fig. IV) of the lower roll B² of roll system B, and any suitable couplings or connections 125 b² establish operative connection between said trunnion b' and gear a¹⁰. A spur-gear a¹¹ is arranged above and parallel and meshes with spur-gear a¹⁰. Gear a¹¹ is operatively connected, by suitable couplings or connections b³, with one of the trunnions b⁴ of the upper roll B' of roll system B. The arrangement and relative size of the gear-wheels employed in establishing operative connection 130

between the engine-shaft and rolls A', A⁺, B', and B² are preferably such that the rolling or operating surfaces of said rolls shall be driven at the same speed or nearly so.

5 The two rolls B' B² are driven in opposite directions, respectively, as already indicated, and the upper roll B' and the lower roll B² are driven in the same direction as the upper roll A' and lower roll A⁺, respectively, of roll 10 system A, and hence the work can be fed from rolls A' A⁺ to rolls B' B², or vice versa, according as the driving-shaft is actuated in the one direction or the other, and the two 15 systems of rolls are preferably arranged in sufficiently close proximity to each other to enable the one system of rolls, as already indicated, to operate upon the work before the latter has left the other roll system.

The bottom roll B² of roll system B is suitably supported from the two housings G G, arranged a suitable distance apart at opposite sides, respectively, of the work's path, and suitably tied together and braced apart by rods G³. It is obvious that for work of 20 the character indicated one or both of the horizontal web-reducing rolls must be adjustable vertically, and the upright side rolls D and D must be adjustable apart, and in the case illustrated the top roll B' is adjustable 25 toward and from the bottom roll B², and it is also obvious that the said upright rolls D D and the top roll B' are preferably adjusted simultaneously relative to the work's path, and the said upright side rolls, in adjusting 30 them apart simultaneously with the adjustment of the top roll, must be moved more rapidly than the top roll in order to avoid long crop ends and torn or cracked flange edges on the finished product.

40 I have found that good results are obtained by moving rolls D and D considerably (and preferably about thirty-three and one-third per cent.) faster than the movement of the top roll B during the adjustment of said rolls. It is obvious that the rolls at the 45 commencement of the operation of the mill are set as required to accommodate the passage between them of the heated blank, and generally in the first pass of the work little more 50 is accomplished than a straightening of the blank.

I would here remark that if the rolls D D in their movement toward and from each other were traveling at the same rate as the 55 travel of the top roll toward and from the bottom roll all of the said rolls will have traveled the same distance, and if, for instance, the rolls were set, say, for a finished product to have one-half inch thickness of web 60 and a half-inch thickness of flange the top horizontal roll B' would at the completion of the work be brought within that distance of the bottom horizontal roll and the side rolls D D would be brought within that distance 65 of the ends of the horizontal rolls that form, as already indicated, the inner sides of the flanges or heads and web of the work. Now

if the top roll in its movement toward the bottom roll moves at the same rate that each of the side rolls moves in the latter's movements toward each other, and if the top roll's travel during the rolling of the work is two and one-half inches it follows that after the top roll has traveled two and one-half inches all of the rolls B D D' will have traveled the 70 same distance and the top roll B' will be three inches from the bottom roll B² and the side rolls D D will be the same distance—namely, three inches—from the flange-rolling 75 surfaces of the horizontal rolls B' B². Now 80 it is evident that if an even reduction of all parts of the work is to be effected and the travel of the top and side rolls during the adjustment of the said rolls were the same, not only had no allowance been left for overcom- 85 ing the distortion caused by the shear in cropping or cutting the blank, which is always much greater on the flanges than on the web, but long crop ends will be had on the finished product. This subject of long crop ends will 90 be readily understood upon consideration of the fact that the flange-rolling surfaces of the horizontal rolls B' B² always rotate more slowly than the peripheral or web-rolling surfaces of said rolls, because the flange-rolling 95 surfaces of said rolls extend nearer to the axes of the rolls than the latter's web-rolling surfaces, and if the side rolls D D are not caused to work more vigorously than the horizontal rolls the finished product will probably 100 be found cracked or torn at the edges of the heads or flanges and a great deal of material that should be equally or properly distributed between the web and flanges, and thereby increase the length of the perfect product, will 105 110 have been robbed by the web-rolling surfaces of the horizontal rolls to form extensive elongations of the web at the ends of the product, which elongations or "crop ends" have to be cut off and are not worth any more than scrap material, and if the edges of the flanges or 115 heads are mutilated the whole product is practically worthless and forms very expensive scrap. Instead, therefore, of desiring only to reduce the flanges at the same rate as the web 120 I have found it invaluable to reduce the flanges considerably faster than the web in order to make up for the much slower rate of delivery at the points of the horizontal rolls from which the edges of the flanges are delivered 125 from the speed of those parts of the horizontal rolls at which the web is delivered, and when the side rolls D D are adjusted toward each other more rapidly to the extent required than the movement of the top roll B' relative to the bottom roll B² it will be found 130 that cracking or tearing of the edges of the flanges of the product will always be avoided. Hence by traveling the side rolls about thirty-three and one-third per cent. more rapidly in the setting of the said rolls than the top roll in the aforesaid two-and-one-half-inch travel of the top roll during the reduction of the work there will be room for the admittance of, say,

at least three-eighths of an inch more material into each of the flanges and a further allowance of one-fourth inch to a side to accommodate any distortion of the blank or work, 5 and the latter can be finished without torn or cracked edges and without long crop ends on the finished part. The additional material going into the flanges, it will be observed, is instrumental in adding to the length of the 10 finished product (flanges as well as web) and is not robbed by the web for the objectionable purpose already indicated. Before referring to the mechanism employed for effecting the adjustment of said adjustable 15 rolls B' D D, I would remark that live surfaces should be present to all sides of the work, and consequently all of said rolls and the bottom roll B² should be rotated positively and in unison. A suitable operative connection 20 between each of said upright rolls D and D and the adjacent trunnion of the upper horizontal roll B' comprises, preferably, a horizontal friction-disk d, (see Fig. IX,) operatively connected with the respective upright 25 roll in any approved manner and preferably by the formation of interlocking lugs d³ and D³ (see Figs. IX and X) upon said friction-disk and the roll, respectively. The upright roll is bored centrally, as at D⁴, and the lugs 30 D³ are formed upon the upper portion of the surrounding wall of said bore. The friction-disk is therefore arranged within or extends into the upper portion of the bore through the roll, and the aforesaid interlocking lugs 35 are arranged vertically to accommodate an up-and-down movement or adjustment of the friction-disk for the purpose hereinafter made more apparent. Said friction-disk d at its upper end is provided with an external annular friction-surface d², that is frictionally engaged by a corresponding annular friction-collar B³, formed upon or operatively connected with the adjacent trunnion of the upper horizontal roll B'. By means of the vertical 40 adjustability of disks d frictional engagement is maintained between said friction members and the friction-collars B³ upon vertically readjusting the upper horizontal roll B'. The frictionally-engaging surfaces of 45 members d and B³ are shown arranged horizontally. The friction-surface of each member B³ is formed upon the periphery of the said member, and the friction-surface of each disk d is formed upon the top of the said member d. The said arrangement of the frictionally-engaging surfaces of members d and B³ maintains a desirable adequacy in the contact 50 between the said friction members during the adjustment of the vertical side rolls 60 toward and from the horizontal rolls and during the adjustment of the top web-reducing roll toward and from the lower web-reducing roll, and the friction-surface of disk d is preferably sufficiently wider than the friction-surface of members B³ to maintain the entire 65 width of the friction-surface of members B³

in contact with disk d in the different adjustments of the side rolls.

The means acting to elevate each friction-disk d and maintain frictional engagement 70 between said friction-disk and the engaging friction-collar B³ comprises, preferably, a piston E, (see Figs. IX and X,) that is secured to the said disk d in any approved manner. The piston extends downwardly into the chamber f, formed in the vertical cylindrical lug or cylinder F, formed upon the inner end of a horizontally-arranged slide H, and upon said cylinder the upright roll that is operatively connected with the aforesaid friction-disk d 75 is mounted. A port or passage-way f' for conducting water or fluid under pressure to chamber f is formed in any approved manner within the lower head of said cylinder and communicates with the aforesaid chamber. The fluid under pressure within said chamber acts to force the piston upwardly, and thereby causes the horizontal friction-disk d to be held in frictional contact with the engaging friction-disk B³ and can, if desired, 80 assist in supporting the top roll B'. A stuffing-box F' is provided around the piston at and supported by the upper end of cylinder F and prevents upward leakage of the fluid under pressure from chamber f. An improvement that constitutes a portion of the novel matter contained in this application consists in positively preventing piston E from rotating with the friction-disks borne by the said pistons, and thereby avoid wear of the packing or stuffing box that encircles the said piston. Each piston E is therefore prevented from turning by a key E', that engages a recess f³, formed in the upper end of the gland f⁴ of the stuffing-box F', formed between the 90 said piston and the embracing cylinder, and the said key extends into a groove e, formed in and arranged longitudinally of the piston. Member f⁴ is bolted, as at f⁵, or otherwise rigidly secured to the cylinder, and groove e 100 is long enough to accommodate the vertical adjustability of the piston, and the friction-disk that is carried by the said piston is rotatably mounted upon the piston and rests, preferably, upon a series of antifriction-rollers e², suitably interposed between the under side of the disk and the upper side of a collar E², formed upon the piston. 105

Each housing G, near its lower end, adjacent to the trunnion of the lower horizontal roll, (see Fig. III,) is provided with a horizontally-arranged slideway G', engaged by a slide H, that carries one of the side rolls D. Slideways G' G' are arranged parallel, therefore, with the direction in which the side rolls D and D are 115 adjustable—that is, two horizontally-movable slides H H are arranged or extend within the different housings, respectively, and each of the said slides carries a side roll that is supported from the said slide in any approved 120 manner. Both slides H H are adjustable toward and from each other, and the two rolls 125

DD are moved, therefore, toward or from each other. Each slide H is operatively connected at its central portion with a screw H², arranged parallel with the slideways for the said slide. 5 The said screw H² engages, preferably, a correspondingly-threaded nut I, (see Fig. III,) rigidly secured within a recess H', formed in the outer and central portion of the slide, and the nut-bearing portion of the slide consists 10 of a piece that is suitably connected with, but has an adjustment independently of, the slide's portion that carries a side roll, and the said outer slide member carries the thrust-bearing for the said side roll, and the said 15 thrust-bearing comprises two large vertical antifriction-rollers J J, arranged a suitable distance apart at the outer side of and engaging the said side roll, and thereby sustaining the said roll against lateral outward pressure 20 during the roll's operation. The said sustaining-rollers are supported from the outer slide member in any approved manner. Studs or bolts h are screwed into and rigid, therefore, with the inner or roll-bearing slide member 25 and extend freely through the outer or roller-bearing slide member. The space h' had between the two slide members accommodates the adjustment of the outer or roller-bearing slide member upon the said bolts or studs 30 toward the inner or roll-bearing slide member. The adjustability of the roller-bearing slide member accommodates the taking up of any wear of the said roll and rollers and the maintenance of the rollers in contact with the 35 roll, and the roller-bearing slide member is retained in the adjustment required to hold its rollers in contact with the roll by nuts h², mounted upon the studs or bolts at the outer end of the said slide member. The slide-operating screw H² extends from the connected slide outwardly through a yoke-forming beam or piece G², that connects together and is removably secured to the two legs of the housing that supports the said slide. Two collars H³ H³, that are fixed or formed upon the screw at opposite sides, respectively, of the said yoke, prevent endwise movement of the screw during the latter's rotation. It will be observed by the construction hereinbefore described 45 that the said screw H² is not only instrumental in adjusting the connected slide H, and consequently the roll carried by the said slide, relative to the web-reducing rolls, but is also employed in adjusting the outer 50 roller-bearing member of the said slide inwardly toward the inner or roll-bearing member of the slide for the purpose hereinbefore indicated. The means removably securing yoke G² to the housing-legs comprises, preferably, studs g, that extend through the yoke into the said legs, keys g', that extend through or partially through the said legs into or through the studs g, and nuts g², mounted upon the studs at the outside of the yoke. 55 The peculiar means hereinbefore described relative to the construction and operation of a slide H and connected parts is exceedingly

simple and forms a portion of the novel matter contained in this application. It is obvious that each slide H and the roll supported thereby are adjusted toward or from the pair of horizontal rolls B' B² according as the connected screw is turned in the one direction or the other. 70

The upright screws L L (see Figs. I, II, and VI) engage correspondingly-threaded holes formed in the tops of housings G G and are arranged to form stops that limit the upward movement or elevation of the upper horizontal roll B'. Saddles are interposed between 80 the lower ends of said screws and the trunnions of said roll, and one of the said saddles is shown and marked l in Fig. VI. Each trunnion of the top roll is supported in the same manner, and referring to Fig. VI, that shows 85 one of the trunnions of the said roll, it will be observed that the support for the said roll comprises a half-box l' under each trunnion of the roll and resting upon upright bars l², that at their lower ends are supported from the 90 one end of a vertically-tilting weighted lever l³, whose weight l⁴ somewhat more than counterbalances the said roll and any load carried by the roll. 95

My present invention involves, broadly, the particularly-illustrated mechanism employed in attaining the required greater reduction of the space between the side rolls than between the top and bottom rolls during the setting of the said rolls. 100

The mechanism employed for rotating screws L and H² is shown to be as follows: Upon the upper end or portion of each screw L (see Figs. I, II, and VI) is operatively mounted a worm-wheel L', that meshes with a worm M', formed upon a suitably-supported horizontally-arranged shaft M. The upper ends of screws L are in the case illustrated angular in cross-section and extend through corresponding holes in the central portions of the engaging wheels L', so that the said screws are capable of endwise movement independently of the said wheels L' without interrupting operative connection between the said wheels and screws. Upon the outer end of each screw H² of a slide H (see Figs. I, III, and VI) is operatively mounted a worm-wheel H⁵, that meshes with a worm h⁵, formed upon a suitably-supported upright shaft h⁴. Each shaft h⁴ is operatively provided at its upper end with a bevel-gear h⁶, that meshes with a bevel-gear m⁶, operatively mounted upon the shaft M, that is suitably driven in the one or other direction, according as screws L, and consequently the top roll B', are to be elevated or lowered. By the construction just hereinbefore described it will be observed that all of the said screws L and H² are operatively connected with one and the same shaft M and are consequently operated simultaneously. 115 All the gears h⁶ and m⁶ correspond diametrically, and the screws L and H² have the same pitch; but the worm-engaged worm-wheels H⁵ employed in the adjustment of the side rolls 120 125 130

have a diameter that is about three-fourths of the diameter of the worm-wheels L' that are instrumental in the operation of screws L . Hence in the case illustrated the more rapid 5 endwise movability of screws H^2 is due solely to the difference in diameter between worm-wheels L' and H^5 . Of course the members of the mechanism establishing operative connection between the reversible shaft M and 10 screws H^2 and L are preferably so arranged that the side rolls $D D$ and top roll B' shall be simultaneously shifted inwardly or outwardly, according as the said shaft is rotated in the one or the other direction, and the 15 said rolls are set as required at the commencement of the operation of the mill upon a predetermined size of blank to form the initial passage-way between the said side rolls and between the top and bottom rolls for the said 20 blank, and the said adjustable rolls are adjusted as required to reduce the said space after each subsequent pass of the said blank.

Rolls A' and A^+ of roll system A (see Figs. I, VII, and VIII) are of course arranged in 25 the same vertical plane, and roll A' has its trunnions resting in half-boxes A^4 , movable up and down within the two upright housings A^5 , that are arranged at opposite sides, respectively, of the work's path. Half-boxes 30 A^4 rest upon and are consequently supported from any suitable number of upright bars or rods A^6 , (see Figs. V and VII,) operatively connected at their lower ends with vertically-tilting weighted levers A^7 , whose weights A^8 somewhat more than counterbalance the weight 35 of roll A' and act in the direction required to elevate said roll. Saddles or blocks A^9 rest upon the trunnions of roll A' above half-boxes A^4 , and suitably-operated screws A^{10} 40 engage correspondingly-threaded holes in the removable tops or caps of the housings and engage the upper surfaces of saddles A^9 and not only limit the upward movement of roll A' , but are instrumental in lowering the said 45 roll against the action of weights A^8 . Roll A' is adjustable vertically, therefore, as required preparatory to operating upon the edges of the heads or flanges of a predetermined piece of work. Screws A^{10} when they 50 are rotated or turned are operated uniformly, and the mechanism employed for uniformly operating said screws comprises, preferably, two worm-wheels $A^a A^b$, operatively mounted on the different screws, respectively above 55 the housings, and meshing with beveled worms A^b , that are formed upon a horizontally-arranged shaft A^c , suitably supported above and from the housing-tops, and the arrangement of the said worms relative to the 60 said gears A^a is such that the screws when the said shaft is rotated are simultaneously turned in the same direction.

A gage for regulating the width of the heads or flanges of the work is provided, and 65 comprises, preferably, two collars $i i$, (see Figs. VII and VIII,) mounted upon the roll A' and roll A^+ , respectively, of roll system A at oppo-

site sides, respectively, of the path of and arranged to engage the web of the work between the paths of the work's flanges or heads. 70 Each collar i is removably and operatively mounted upon the central portion of the respective roll. The collar's end portions are diametrically smaller than the collar's central portion and form the flange-edge-rolling 75 portions of the roll. The collar is placed upon the roll by sliding it endwise onto the core of the roll, and the operative connection between the core and the collar consists, preferably, of any suitable number of keys i' , engaging opposing grooves $i^2 i^2$, formed in the collar and core, respectively. The rolls A' and A^+ , with their collars $i i$, are adapted for making a particular size or width of flanges, but any other size can be made by removing 80 the said collars and substituting other collars required for the desired particular size. The size of the said collars $i i$ determines, as already indicated, the width or size of the product's flanges. The collars assist also in straightening or removing irregularities in 85 and in removing scales from the web of the work and are so shaped that they will engage and assist in finishing the inner sides of the flanges of the work. Two horizontal bars c are arranged at opposite sides, respectively, of and parallel with the lower flange-edge-rolling roll A^+ and below and transversely of the under side of the work's path. Each bar c bears two rollers $c' c'$, supported from the bar a suitable distance apart and arranged next below the path of opposite flanges, respectively, of the work. Between 90 each pair of rollers $c' c'$ is provided a bottom guide c^2 , arranged to be engaged by and guide 95 the under side of the work's web, and the said guide straddles and is removable upwardly from the bar that bears the said rollers. A guide c^2 and rollers $c' c'$ are therefore 100 at each side of roll A^+ , and the two guides and the two pairs of rollers are instrumental 105 in guiding the work to and from the flange-edge-rolling rolls. The means removably securing the housing-caps A^d to the legs of the housings comprises, preferably, studs A^e , extending through the caps into the housing-legs, keys A^g , extending through or partially through the said legs into or through the 110 studs, and nuts A^h , mounted upon the studs at the upper sides of the caps. By removing the housing-caps the rolls $A' A^+$ and guides $c^2 c^2$ can be readily removed for repairs and the placing of other collars upon the rolls. 115

I would have it understood that the details of construction relative to roll system A are 120 desirable and valuable, and the said details to the extent pointed out in the claims form a portion of the novel subject-matter of this application. Feed-table C^2 comprises any suitable number of feed-rollers C^4 , that are 125 driven in any approved manner and as required to feed the work to and from the said roll system A from and to the said table. To remove scales from the work that can be 130

readily removed by a tumbling process, the work when it is upon table C² is automatically overturned any suitable number of times, and this process of tumbling the work is valuable also in assisting in the production of uniform work.

The particular means employed for overturning the work upon table C² forms a portion of the subject-matter claimed in this application, and comprises, preferably, (see Figs. XI and XII,) an oscillating shaft C⁷, that is suitably supported below and arranged horizontally and longitudinally of the table and is provided at two points located a suitable distance apart with two arms C⁸ C⁹, extending transversely of the table and arranged to engage the work upon the table from below and throw the work laterally against the inclined uprights or backs C⁹, with which the table is provided. Each arm C⁸ of shaft C⁷ is arranged to operate between two adjacent feed-rollers of the table, so that said rollers shall not interfere with the location and operation of the said arm. Arms C⁸ in their normal or inoperative position are below the path of the work that in solid lines, Fig. XII, is shown resting upon the feed-rollers of the table and in dotted lines in same figure is shown thrown laterally against the inclined surfaces of backs C⁹, which inclined surfaces extend upwardly and outwardly from their lower extremities. Each arm C⁸ has its outer portion bent or extending upwardly, so that the said outer portion when the work is thrown against backs C⁹, shall overlap the work and prevent the latter from rebounding back into the same position upon the table, and the inclined surfaces of members C⁹ are sufficiently far from a perpendicular that the work when the work-tumbling arms are returned below the table will fall with its opposite side upon the table. The said overturning operation is repeated, if desired, any suitable number of times and is very effective in shaking scales from the work. The means for oscillating the work-overturning shaft C⁷ comprises, preferably, (see Fig. XII,) a gear C¹⁰, that is operatively mounted upon the shaft, preferably at some point between the two arms C⁸ C⁹, and the said gear meshes with a reciprocating rack C¹¹, that is arranged transversely of the feed-table, between two adjacent feed-rollers of the said table, and attached in any approved manner to the rod C¹² of the piston C¹³ of a hydraulic engine or motor C¹⁴. In order to render the action of the extremities of arms C⁸ easy in overturning the work upon table C², each of said arms at its outer end is provided with a wheel or roller C¹⁵, that engages the work in the overturning operation and prevents the arm from holding onto or detaining the work during the said operation, and in order to render the overturning of the work still more positive and positively insure the overturning of the work during the overturning operation of the arms C⁸ one or more hydraulic

cylinders C¹⁶ are provided. In the case illustrated two cylinders C¹⁶ are arranged a suitable distance apart and at right angles 70 to table C² at the rear of backs C⁹. Each cylinder C¹⁶ is provided internally with a piston C¹⁷, capable of reciprocating endwise of the cylinder's chamber and actuated by fluid under pressure admitted to the cylinder in 75 any approved manner, and the said piston has its rod C¹⁸ extending forwardly, and the said rod when actuated forwardly engages the lower portion of the work from the rear and participates in the overturning of the 80 work and renders the overturning operation infallible. C¹⁹ designates a forward side guide for the work in the latter's passage over table C² and is of course arranged along the forward side of the work's path. 85 The forward or outer end of each rod or pushing device C¹⁸ is provided, preferably, with an upright arm C²⁰, that is pivoted horizontally and transversely at C²¹ to the said rod, and at the rear of its axis is provided 90 with a weight or poise C²², that acts to retain arm C²⁰ in the latter's upright or normal position. The said weight C²² normally straddles the rod C¹⁸ and engages the upper side of the rod, and the said arm cannot therefore tilt rearwardly beyond its normal position. The arrangement of parts is such that the said arm when in its normal position projects above the table far enough to engage upon being actuated forwardly the 100 lower portion of the work thrown against backs C⁹ and participate in overturning the work upon the said table, and the work when overturned tilts the said arm forwardly and downwardly out of the way if the said arm 105 is struck by the overturning work, and hence the said arm is not injured in case it is struck by the overturned work.

Two suitably-formed bottom guides or bearings Q Q' (see Figs. I, II, III, and VI) for the 110 work are provided at opposite sides, respectively, of rolls B' B² of roll system B at the under side of the path of the work. A suitably-driven roller j is arranged horizontally and transversely of the under side of the work's 115 path between roll system A and roll system B, and the guide Q' is arranged between the said roller j and roll B² and extends into close proximity to the said roll B². Guide Q is arranged between roll B² and table C' and extends into 120 close proximity to the said roll. Said guides prevent downward displacement of the work in the latter's passage to and from roll system B.

A top guide (not shown) for the work in the 125 passage of the work from the roll system B to the roll system A is preferably provided for the purpose of preventing the work from being thrown upwardly out of its path in said passage; but as the top guide that I prefer to 130 employ in the place indicated involves considerable mechanism and does not form any portion of the subject-matter claimed in this application and would if it were illustrated

in this application confuse other combinations of parts hereinafter claimed I have not shown it in this application.

It is obvious that, as already indicated, the 5 top web-reducing roll B' and with it the flange-reducing rolls D D are set preparatory to the first pass of a heated blank that requires reducing the distance apart required for the first pass, which distance forms the largest 10 work-receiving passage between said rolls during the reducing operation upon the blank, and said passage is rendered smaller preparatory to each successive pass of the work, and the rolls after the work has had its finishing 15 pass are again adjusted to enlarge the work-receiving passage between them as required for another blank.

Two side-guide-forming bars r r for the work (see Figs. I, II, III, and VIII) extend 20 from roll system B to and beyond roll system A and are arranged at opposite sides, respectively, of the work's path. Said guides r r extend into close proximity to the rolls of roll system B and a suitable distance beyond the 25 outer side of roll system A into suitable proximity to table C'. Guides r r are parallel, supported as will hereinafter appear, and adjustable apart simultaneously with the shifting of the rolls D and D toward or from each 30 other and to the same extent, or approximately to the same extent, as the movement of the said rolls D D. Bars or guides r r are pivoted vertically at or near their inner ends, as at r', to the different housings G G, respectively, at opposite sides, respectively, of the work's path at any suitable point between roll systems A and B and preferably near the rolls of roll system B, and the said guides are capable of being swung horizontally on their 35 pivotal bearings toward or from each other. Guides r r at the outer sides of and a suitable distance from rolls A' A¹ are operatively connected with each other for the purpose of simultaneously and equally moving the said 40 guides in adjusting the guides apart. A desirable operative connection between the said guides comprises a horizontally-arranged shaft t, that extends transversely of and below the work's path through lugs or flanges 45 r², formed upon and depending from guides r r. A right-handed screw t' is formed upon the shaft t at the outer side of one of the said guides, and a left-handed screw t³ is formed upon the said shaft at the outer side of the 50 other guide. Screws t' and t³ are operatively engaged by two nuts t² and t⁴, respectively. The said nuts have bearing in and are arranged to slide endwise of lugs A⁵, formed upon the housings A⁵, and each of the 55 aforesaid guides is operatively connected with one of the aforesaid nuts r in any approved manner, and in the case illustrated each of the aforesaid guide-lugs slidably embraces the shaft and engages a recess t⁵, formed in the 60 inner end of the connected nut. Shaft t, at or near one end, has bearing in a stationary box A⁶, and a bevel-gear t⁶ is fixed upon the

shaft at the outer end of the said box and meshes with a bevel-gear t⁷, operatively mounted upon a shaft t⁸, that is arranged horizontally and at right angles to shaft t, that, it will be observed, therefore, is stationary so far as endwise movement is concerned. Shaft t⁸ is supported in any approved manner and extends from end to end of the machine. At 70 one end of the machine the said shaft t⁸ carries the gear t⁷ and at the other end of the machine operatively bears a bevel-gear t⁹, that meshes with a bevel-gear T⁹, that is fixed upon shaft T, that is arranged horizontally below and extends transversely of the work's path at the outer side of and a suitable distance from roll B². The aforesaid guides r r between roll system A and roll system B are engaged upon their outer sides by 85 extensions or members r³ r³ of pistons r⁴ r⁴, (see Fig. I,) arranged and operated as required to assist in supporting or moving the said guides r r toward each other simultaneously with the shifting of rolls B' D D'. Guides r r are set as required for the work's initial pass to accommodate the passage of the heated blank between them, and after the first pass the said guides are shifted toward each other preparatory to each pass to 90 reduce the width of the passage-way between them and continue to properly perform their function of guiding and preventing lateral displacement of the work during the operation of the mill upon the work. One member 100 r³ engages and is arranged at the outer side of and at right angles to one of the guides r, and the other member r³ engages and is arranged at the outer side of and at right angles to the other guide r. Each piston r⁴ is 105 arranged to operate within a stationary horizontally-arranged closed chambered cylinder r⁵, that at its outer end has its chamber connected with a pipe r⁶, employed for supplying water or other fluid under pressure to the 110 piston in said cylinder, and thereby actuate the said piston in the direction required to move the engaging guides r laterally and inwardly. Both pipes r⁶ are connected with a main-supply pipe r⁷ by a valve-casing r⁸, and 115 a valve r⁹ (see Fig. I) in said valve-casing interrupts and establishes communication between the main pipe r⁷ and the branch pipes r⁶. Valve r⁹ is operated in any approved manner and is opened to admit pressure or 120 additional pressure to the said cylinders simultaneously or practically simultaneously with the inward shifting of rolls B' D D. Fluid can be removed from within cylinders r⁵ through valved drain-pipes r¹⁰, with which 125 said cylinders are provided. (See Fig. I.)

Two side-guide-forming and work-straightening bars R R for the work (see Figs. I, II, III, and VI) are provided between table C' and roll system B at opposite sides, respectively, of the work's path and extend into close proximity to rolls B' B². Bars R R are pivoted vertically at or near their inner ends, as at R', to the different housings G G, re-

spectively, at opposite sides, respectively, of the work's path at any suitable point between the rolls of roll system B and table C', and preferably near the rolls of roll system 5 B, and the said bars are capable of being swung horizontally on their pivotal bearings toward or from each other. Bars R R, at the outer sides of and a suitable distance from rolls B' B², are operatively connected with 10 each other for the purpose of simultaneously and equally moving the said bars in adjusting them apart. A desirable operative connection between the said bars comprises a horizontally-arranged shaft T, that extends 15 transversely of and below the work's path through lugs or flanges R², formed upon and depending from bars R R. A right-handed screw T' is formed upon the shaft T at the outer side of one of the said bars R, and a 20 left-handed screw T³ is formed upon the said shaft at the outer side of the other bar R. Screws T' and T³ are operatively engaged by two nuts T² and T⁴, respectively. The said nuts have bearing in and are arranged to 25 slide endwise of lugs G⁴, formed upon the housings G, and each of the aforesaid bars R is operatively connected with one of the aforesaid nuts in any approved manner, and in the case illustrated each of the aforesaid 30 lugs R² slidably embraces the shaft and engages a recess T⁵, formed in the inner end of the connected nut. Shaft T, at or near its end that extends adjacent to shaft t⁶, has bearing in a stationary box G⁵, and the bevel- 35 gear T¹⁰ is fixed upon the shaft at the outer end of the said box and meshes with a bevel-gear t⁷, operatively mounted upon the shaft t⁸, as already indicated, and the said shaft T is therefore stationary so far as endwise 40 movement is concerned. Shaft T is operatively provided with a worm-wheel T⁶, that meshes with a worm T', formed upon a diagonally-arranged shaft T⁸, that extends into close proximity to shaft M, (see Figs. I, II, 45 and VI,) and is operatively provided with a bevel-gear T¹⁰, that meshes with a bevel-gear M⁹, operatively mounted upon the said shaft M.

As already indicated, the side guides r r 50 are adjusted about the same distance apart, preparatory to the initial pass of the work, as the side rolls D D, and the said rolls and guides are shifted inwardly simultaneously and to the same or approximately the same extent 55 preparatory to each succeeding pass of the work during the reduction of the work. The straightening-bars R R are adjusted about the same distance apart as the side rolls and the aforesaid side guides preparatory to the 60 initial pass of the work; but the outer or operating ends of the said bars are caused to approach each other more rapidly than the aforesaid side rolls and the aforesaid side guides during the operation of the machine 65 upon the piece of work, so that the work is gradually straightened or kept perfectly straight during the operation of the machine.

The gradual straightening of the work will be found much more desirable than the straightening of the work by the application of force 70 to effect the said straightening at one stroke. By the construction hereinbefore described it will be observed that the straightening-bars R R are operatively connected with the shaft M through the medium of the shaft T, 75 that is operatively connected with the said bars, and the operative connection between the said shaft T and the aforesaid shaft M and the said guides r r are operatively connected with the said shaft M through the 80 medium of the said shaft T and the operative connection between the said shaft T and the said guides. The bevel-gears of the operative connection between the shafts T and M correspond; but the worm and worm-wheel 85 of the said operative connection have such diametrical dimensions and pitch relative to the diametrical dimensions and pitch of the worms and worm-wheels instrumental in the operation of the screws L, that the said shaft 90 T shall (the screws formed thereon being supposed to have the same pitch as the screws instrumental in the adjustment of the top roll B') result in the shifting of the straightening-bars more rapidly than the shifting of 95 the side rolls, and if the side rolls D D are shifted about thirty per cent. more rapidly than the top roll, as desired, then the straightening-bars are shifted more than thirty per cent. more rapidly than the said top roll. In 100 any case it is desired to shift the said bars whenever the side rolls are shifted and in a corresponding direction, so that the said bars whenever the work is passed between the said rolls to and between the said bars act, as required, to maintain the work perfectly straight or to straighten up the work if the latter requires subjection to any straightening operation. The bevel-gear t⁷ of the operative connection between the aforesaid shaft T and 110 the side guides r r is sufficiently larger diametrically than the engaging gear T⁹ to result or assist in the shifting of the said guides (the pitch of the screws instrumental in the shifting of the said guides corresponding with 115 or being less than the pitch of the screws employed in the operation of the aforesaid straightening-bars) less rapidly than the shifting of the said straightening-bars.

To recapitulate, therefore, the side guides 120 r r are shifted at the same or about the same speed as the side rolls D D during the adjustment of the adjustable rolls of roll system B, and the side guides are therefore shifted gradually and correspondingly or approximately correspondingly with the shifting of the side rolls, and the said guides and rolls are shifted more rapidly than the top roll B'. The straightening of the work is gradual, 125 and the gradual straightening, as already indicated, is easier and more effectual. The travel of the side guides is independent of the travel of the side rolls, and it is therefore possible at the beginning of the opera- 130

tion of the machine to have the side guides a sufficient distance apart to permit of an easy entrance of the work.

What I claim is—

5. 1. The combination of two reducing-rolls arranged at an angle to each other; a friction-collar operatively connected with one of the said rolls; a friction-disk operatively connected with the other roll and frictionally engaging the aforesaid friction-collar and movable independently and endwise of the said roll; a piston arranged to bear, at one end, against the said friction-disk and retain the latter in operative contact with the friction-collar; means capable of exerting a continuous pressure upon the other end of the said piston, and means for preventing the rotation of the piston with the connected friction-disk, substantially as set forth. 70
20. 2. The combination with two reducing-rolls arranged at an angle to each other; a friction-collar operatively connected with one of the said rolls; a friction-disk operatively connected with the other roll and frictionally engaging the aforesaid friction-collar and movable independently and endwise of the said roll; a piston arranged to bear, at one end, against the said friction-disk and retain the latter in operative contact with the friction-collar; a fluid-receiving chamber contiguous to the opposite end of the piston; means for conducting fluid under pressure to the said chamber; a stuffing-box formed about the piston, and means for preventing the rotation of the piston with the connected friction-disk, substantially as and for the purpose set forth. 75
25. 3. The combination of two reducing-rolls arranged at an angle to each other; a friction-collar operatively connected with one of the said rolls; a friction-disk operatively connected with the other roll and frictionally engaging the aforesaid friction-collar and adjustable independently and endwise of the roll; a piston grooved externally and longitudinally and arranged to bear, at one end, against the said friction-disk and retain the latter in operative contact with the friction-collar; a fluid-receiving chamber contiguous to the opposite end of the piston; means for conducting fluid under pressure to the said chamber; a stuffing-box formed about the piston; a member projecting from a rigid member of the said box into the piston-groove, and the said groove being long enough to accommodate an endwise movement of the piston, substantially as and for the purpose set forth. 80
30. 4. The combination of two reducing-rolls arranged at an angle to each other; a friction-collar operatively connected with one of the said rolls; a friction-disk operatively connected with the other roll and frictionally engaging the aforesaid friction-collar and adjustable independently and endwise of the roll; a piston arranged to bear, at one end, against the said friction-disk and retain the

latter in operative contact with the friction-collar; means capable of exerting a continuous pressure upon the other end of the said piston; means for preventing the rotation of the piston with the connected friction-disk, and antifriction-rollers interposed between the piston and the said friction-disk, substantially as set forth. 75

5. The combination of a housing; a slide-way formed within the said housing; a slide engaging the said slideway and consisting of two parts; a reducing-roll carried by one of the slide's parts; a lateral bearing for the roll carried by the other slide's part, and the last-mentioned part being adjustable independently of the roll-bearing part and operatively engaged by means for shifting the slide within the slideway, and means for securing the independently-adjustable part in the desired adjustment relative to the roll-bearing part, substantially as set forth. 80

6. The combination of a housing provided with a slideway; a slide engaging the said slideway and consisting of two parts; a reducing-roll supported from one of the slide's parts; rollers sustaining the roll and carried by the slide's other part, and the sustaining-roller-bearing part being adjustable independently of and toward and from the roll-bearing part; studs or bolts extending easily through the independently-adjustable part and supported from the roll-bearing part, and nuts upon the studs at the outer end of the said adjustable part, substantially as shown, for the purpose specified. 85

7. In rolling apparatus of the character indicated, the combination of the vertically-shiftable top roll; the bottom roll; the side rolls arranged at opposite ends, respectively, of the top and bottom rolls; means acting to elevate the top roll; screws for lowering the said top roll; stationary members having correspondingly-threaded holes engaged by the said screws; a suitably-driven shaft operatively connected with the said screws; two slides carrying the different side rolls, respectively, and shiftable toward and from each other; nuts fixed to the outer ends of the said slides; screws engaging the said nuts and held stationary so far as endwise movement is concerned; worm-wheels operatively mounted upon the last-mentioned screws, and upright shafts intergeared with the first-mentioned shaft and provided with worms engaging the said worm-wheels, and the said last-mentioned worms and worm-wheels having such size relative to the size of the first-mentioned worms and worm-wheels that the aforesaid slide-screws shall be rotated more rapidly than the top roll-shifting screws, substantially as and for the purpose set forth. 90

8. In rolling apparatus of the character indicated, the combination with the two flange-edge-rolling rolls arranged the one above the other; of two bars arranged at opposite sides, respectively, of the lower roll below the work's path; rollers supported from the said bars

and having the arrangement required to be engaged by the flanges of the work when the latter is passed between the rolls, and bottom guides removably supported from the said 5 bars between the rollers upon the bars and arranged to be engaged by the under side of the work's web during the work's passage between the rolls, substantially as set forth.

9. In a rolling-mill of the character indicated, the combination with a table having at one side a back or backs C⁹; of a suitably-actuated device; mechanism or apparatus for overturning or throwing the work, that is upon the said table, laterally against said 15 back or backs, and a suitably-actuated device, or devices, for engaging the work thrown against said backs and instrumental in effecting the complete overturning of the work, substantially as set forth.

10. In a rolling-mill of the character indicated, the combination with the table having a back or backs C⁹ at one side of the work's path over said table; of a suitably-actuated device, mechanism or apparatus for overturning or throwing the work, that is upon the 25 said table, laterally against the said back or backs, and suitably-actuated rods or devices arranged to push upon the work's side thrown against the said back or backs, substantially 30 as and for the purpose set forth.

11. In a rolling-mill of the character indicated, the combination with a table over which the work is passed; of a suitably-actuated device, mechanism or apparatus for 35 engaging the under side of the work that is upon said table and tilting the work laterally and upwardly, and a suitably-actuated device or devices, arranged to push upon the lower portion of the opposite side of the work 40 when the latter is tilted as aforesaid, substantially as and for the purpose set forth.

12. In a rolling-mill of the character indicated, the combination with a table over which the work is passed; of a suitably-actuated 45 device, mechanism or apparatus for engaging the under side of the work that is upon the said table and tilting the work laterally and upwardly, and any suitable number of suitably-actuated rods arranged to 50 push upon the lower portion of the opposite side of the work when the latter is tilted as aforesaid, and each of the said rods, at its free end, being provided with an upright arm pivoted transversely to the rod, and the said 55 arm being free to tilt forwardly or outwardly and provided with means that acts to retain it in its upright or normal position and forms a stop for limiting the tilting of the arm in the opposite direction, substantially as and 60 for the purpose set forth.

13. In a rolling-mill of the character indicated, the combination of a system of rolls arranged to operate upon the work's web and upon the inner and outer sides of the flanges 65 of the work, and another system of rolls arranged to operate upon the edges of the flanges of the work, and located a short dis-

tance from the first-mentioned roll system: of two side guides arranged at opposite sides, respectively, of the work, and the said guides 70 being vertically pivoted at one end and extending between the two roll systems at opposite sides, respectively, of the work's path; mechanism for simultaneously shifting the said guides upon their axes toward or from 75 each other, and pressure-exerting devices arranged to bear upon the outer sides of the guides at an intermediate point, substantially as set forth.

14. In rolling apparatus of the character indicated, the combination with a vertically-shiftable top web-reducing roll B', the bottom web-reducing roll B², and the two upright flange-reducing rolls D D arranged at opposite ends, respectively, of the top and bottom 85 rolls; of means for vertically shifting the top roll; means for shifting the side rolls toward and from each other simultaneously with and more rapidly than the shifting of the top roll; two laterally-shiftable guides arranged at opposite sides, respectively, of the work's path, and independent of the side rolls, and mechanism for shifting the said guides toward or from each other simultaneously, and at the same, or approximately the same, speed as 90 the shifting of the aforesaid side rolls, substantially as set forth.

15. In rolling apparatus of the character indicated, the combination with the top web-reducing roll shiftable vertically; the bottom 100 web-reducing roll; two upright flange-reducing rolls, arranged at opposite ends, respectively, of the top and bottom rolls and shiftable toward or from each other; of a suitably-driven shaft; screws instrumental in the 105 shifting of the top roll and operatively connected with the said shaft; screws instrumental in the shifting of the side rolls and operatively connected with the said shaft, and two 110 guides arranged at opposite sides, respectively, of the work's path and supported independently of the side rolls, and mechanism for simultaneously shifting the said guides toward or from each other and operatively connected with the aforesaid shaft, substantially 115 as set forth.

16. In a rolling-mill of the character indicated, the combination of a system of rolls arranged to operate upon the work's web and upon the inner and outer sides of the flanges 120 of the work, another system of rolls arranged to operate upon the edges of the flanges of the work and located a short distance from the first-mentioned roll system; two side guides arranged at opposite sides, respectively, of 125 the work at one side of the first-mentioned roll system; two laterally-shiftable work-straightening bars arranged at opposite sides, respectively, of the work and at the opposite side of the said last-mentioned roll system, 130 and mechanism for simultaneously actuating the said bars toward or from each other, substantially as set forth.

17. In a rolling-mill of the character indi-

- cated, the combination of a system of rolls arranged to operate upon the work's web and upon the inner and outer sides of the flanges of the work; another system of rolls arranged 5 to operate upon the edges of the flanges of the work and located a short distance from the first-mentioned roll system; two laterally-shiftable side guides arranged at opposite sides, respectively, of the work at one side of 10 the first-mentioned roll system; two laterally-shiftable work-straightening bars arranged at the opposite side of the said last-mentioned roll system, and mechanism for simultaneously actuating the said bars and guides inwardly or outwardly, substantially as and for 15 the purpose set forth.
18. In a rolling-mill of the character indicated, the combination of a system of rolls arranged to operate upon the work's web and 20 upon the inner and outer sides of the flanges of the work; another system of rolls arranged to operate upon the edges of the flanges of the work and located a short distance from the first-mentioned roll system; two laterally- 25 adjustable side guides arranged at opposite sides, respectively, of the work at one side of the first-mentioned roll system; two laterally-adjustable work-straightening bars arranged at the opposite side of the said last-mentioned 30 roll system, and mechanism for simultaneously adjusting the said bars and guides, and moving the bars more rapidly than the guides during the adjustment of the guides and bars, substantially as set forth.
19. In rolling apparatus of the character indicated, the combination with a vertically- 35 shiftable top web-reducing roll B'; the bottom web-reducing roll B², and the two upright flange-reducing rolls D D arranged at 40 opposite ends, respectively, of the top and bottom rolls; of means for vertically shifting the top roll; means for shifting the side rolls toward and from each other simultaneously

with and more rapidly than the shifting of the top roll; two laterally-shiftable work- 45 straightening bars arranged at opposite sides, respectively, of the work's path, and mechanism for shifting the said bars simultaneously, or approximately simultaneously, with but more rapidly than the side rolls during 50 the adjustment of the adjustable rolls, substantially as and for the purpose set forth.

20. In rolling apparatus of the character indicated, the combination with the top web-reducing roll shiftable vertically; the bottom 55 web-reducing roll, and two upright flange-reducing rolls, arranged at opposite ends, respectively, of the top and bottom rolls and shiftable toward or from each other; of means for vertically shifting the top roll; means for 60 adjusting apart the side rolls simultaneously with the adjustment of the top roll, and shifting the side rolls more rapidly than the top roll is shifted during the adjustment of the said rolls; two guides arranged at opposite 65 sides, respectively, of the work's path at one side of the bottom roll; mechanism for adjusting apart the said guides simultaneously with the adjustment of the aforesaid rolls; two work-straightening bars arranged at opposite sides, respectively, of the work's path and at the other side of the bottom roll, and mechanism for adjusting apart the said bars simultaneously with the adjustment of the aforesaid rolls and shifting the bars more 70 rapidly than the side rolls are shifted during the said adjustment, substantially as and for the purpose set forth.

In testimony whereof I sign this specification, in the presence of two witnesses, this 2d 80 day of October, 1897.

HENRY GREY.
